Des. 228,396

Patented Sept. 18, 1973

228,396

GOLF PUTTER HEAD

Nicholas A. Cruger, Altamonte Springs, Fla. (205 W. Fairbanks Ave., Winter Park, Orange County, Fla. 32789)

Filed July 19, 1971, Ser. No. 164,185

Term of patent 14 years

Int. Cl. D21—02

U.S. Cl. D34—5 GH

Fig. 1

Fig. 2

Fig. 3

Fig. 4

Fig. 5

FIG. 1 is a side elevation view of a golf putter head showing my design.

FIG. 2 is a side elevation view.

FIG. 3 is an end elevation view.

FIG. 4 is a perspective view.

FIG. 5 is a side elevation view of a modified embodiment, which embodiment adds a slot as shown without changing any other features of the design.

I claim:

The ornamental design for a golf putter head, substantially as shown and described.
